Primary Examiner—Louis S. Zarfas**Assistant Examiner—I. Simmons****[57]****CLAIM**

The ornamental design for a combined suction based needle re-sheath and winged needle split top cap with tubing anchor, as shown and described.

DESCRIPTION

FIG. 1 is a perspective view of a combined suction based needle re-sheath and winged needle split top cap with tubing anchor showing my new design, shown in separated condition;

FIG. 2 is a perspective view thereof shown in assembled condition, the broken line showing of the winged needle and tube are for illustrated purposes only and forms no part of the claimed design;

FIG. 3 is a top plan view thereof;

FIG. 4 is a bottom plan view thereof;

FIG. 5 is a rear elevational view thereof;

FIG. 6 is a cross-sectional view thereof, taken along the line 6—6 of FIG. 3;

FIG. 7 is a front elevational view thereof;

FIG. 8 is a perspective view of the winged needle split top cap with tubing anchor, shown in separated condition for ease of illustration;

FIG. 9 is a cross-sectional view thereof, taken along the line 9—9 of FIG. 10;

FIG. 10 is a top plan view thereof; and,

FIG. 11 is a front elevational view thereof.
